Joseph J. O'Brien

UNITED STATES PATENT OFFICE.

JOSEPH J. O'BRIEN, OF SPRINGFIELD, MASSACHUSETTS.

METHOD OF PREVENTING OVERFLOW ON LOWLANDS LYING ADJACENT TO A STREAM.

Application filed September 30, 1918. Serial No. 256,357.

To all whom it may concern:

Be it known that I, JOSEPH J. O'BRIEN, a citizen of the United States of America, and resident of Springfield, in the county 5 of Hampden and State of Massachusetts, have invented certain new and useful Improvements in Methods of Preventing Overflow on Lowlands Lying Adjacent to a Stream, of which the following is a full, 10 clear, and exact description.

This invention relates to improvements in methods and means for regulating the flow of rivers and streams for the purpose of preventing the river and stream 15 flow from over flowing the banks, breaking through the banks, and destroying levees and other retaining works, with the result of wide spread inundation and loss of lives and property.

Various systems have been applied to regulate river and stream flow and to prevent losses due to floods, but practically all of these systems have involved some 20 sort of variation, elevation, extension or strengthening of the river or stream banks, or flow directing works intended to locally 25 intensify the velocity of stream flow.

During the flood season the channel of a river is congested with the flood waters 30 and the capacity of the channel to accommodate the inflowing waters is exceeded, with the result that the flood waters overflow the river banks and inundate the surrounding country.

The velocity which a stream attains during the period of normal flow or during the period of flood flow is produced by the effective head in the river channel, resulting from the grade of the channel and the volume of 35 water moving therein. When this head is at its maximum the velocity of the river flow, due to its own conditions and forces, cannot increase, so that the capacity of the channel cannot be increased while this 40 velocity remains constant.

The problem of controlling river floods has thus far been considered as a problem of widening, deepening, or increasing the extent of the river channel.

The writer has discovered, through long 50 study and research that the problem can be solved by increasing the velocity of the flow of the river stream, without altering the depth, width, height or character 55 of the river banks.

The capacity of any river channel to accommodate any volume of flood discharge is limited because the velocity attained by the flow of the river during the period prior to flood and during flood is limited 60 by the energy which is generated through gravity acting upon the mass of the river waters.

As a river approaches its mouth its grade decreases and its width increases. The 65 river waters overflow the river banks and levees because the velocity of flow through the river mouth is not sufficient to insure the discharge of all of the flood waters in the channel.

The object of the present invention is to provide practical means and a method of accelerating the velocity of flow of a stream or river so that the total amount of water discharged during a given period will 70 equal the total amount of water required to be discharged to prevent inundation due to excess flood flow overflowing the banks, and inundation will thus be prevented.

In carrying out the process it is not 75 necessary that the total volume of the stream flow be caused to flow at greatly accelerated speed or velocity, as will be later shown, it is only necessary that the total discharge due to flow accelerated by 80 mechanical means shall be sufficient to prevent overflow.

With the above and other objects in view the invention involves certain steps and means shown in the accompanying drawings, 85 which are described in detail in following specification in which:—

Fig. 1 is a plan of a river or stream showing the application of the system or process thereto.

Fig. 2 is a plan showing the general arrangement of the flow accelerating means in a river channel.

Fig. 3 is a plan of a centrifugal pump employed for accelerating the stream flow.

Fig. 4 is a cross section through a river channel, showing a series of pump discharge pipes therein, and means for varying the depth of submersion of such discharge pipes.

Fig. 5 is a detail plan showing the arrangement of a series of pump discharge pipes, in a group of ten.

Fig. 6 is a similar view of a group of thirty pump discharge pipes.

Fig. 7 is a detail view in longitudinal sec-

110

tion of a barge or boat, showing the intake and discharge pipes of a centrifugal pump.

In the river channel A I dispose a series of pump discharge pipes B, which are shown 5 to lead diagonally from the sides of the channel from the centrifugal or other pumps C, which are supported by boats or barges b, or on land, and which are power driven through the medium of an electric motor, 10 steam plant or otherwise as may be found expedient.

In Figs. 5 and 6 I show a specific grouping of a series of pump discharge pipes, wherein 15 the discharge pipes B are positively coupled to each other by welding or other suitable means, and are arranged in parallel relation so as to discharge toward the mouth of the river channel. In Fig. 5 I show a group of ten discharge pipes and in Fig. 6 a group of 20 thirty discharge pipes. These pipes may be any suitable diameter and grouped in any desired relation.

The intake pipe D of each pump is preferably arranged nearer the surface of the 25 water, so that a head of about one or two feet above the intake pipe will be provided. The outlet pipe is preferably directed toward the bed of the stream, so that its current will not interfere with the surface 30 navigation.

In order to regulate the depth of submersion of the discharge pipes I connect each 35 group to a cable E, the ends of which are wound about the winding drums F, which are located on the sides of the river channel or on barges or other supports, and which are power driven, so that the outlets of the 40 discharge pipes may be raised or lowered with reference to the bed of the stream.

The pump discharge pipes may extend for 45 any distance along the river or stream channel, but are preferably arranged near the mouth of the river channel, and so as to discharge their contents into the central parts of the river channel.

It is a matter of applying sufficient energy 50 to the river stream flowing through the channel in order to obtain the necessary velocity to provide for the required maximum discharge through the channel mouth. The amount of pumps necessary the horse power required to operate them to produce the necessary artificial head, and the disposition of the pump discharge and intake pipes is 55 a matter of local engineering study.

The capacity of a stream to transport sediment and rocks increases very rapidly with 60 the increase of its velocity, so that when the high velocity stream moves over the channel bed it will pick up and carry out to sea a great deal of material deposited on the bed, and thus act to enlarge the area of the river channel. This action does not involve a lifting of the materials thus acted on and transported by the pumps as in the case of the

hydraulic dredges, so that the total energy of the pump is effective for direct useful work in transporting this material, when the discharge pipes are so adjusted as to produce a direct erosive action on the channel bed. 70 The depth of submersion of the pump discharge pipes, the velocity of the high velocity stream produced thereby, and the number and adjustment of the discharge pipes will be determined by the depth, area and general nature of the river channel and the character of the discharge into the sea. It is believed that a stretch of say ten miles in one of the passes of the Mississippi River would be sufficient to provide the necessary 80 capacity, and the effect of such discharge would soon be dissipated by the waters of the Gulf into which the Mississippi discharges. The same general rule applies to 85 all other rivers.

The principle involved in the discovery and invention herein set forth is that the carrying capacity of any river or stream channel may be indefinitely enlarged by increasing the head of the stream flow through 90 an artificial system of flow accelerators, such as pumps, and that the whole volume of stream flow need not be placed under such accelerated flow. When only the central section of the river stream is thus accelerated the banks of the river are not seriously eroded, and what erosion does take place is useful to deepen the river channel. 95

The pump discharge pipes may be supported so that they will be held above the 100 bed of the channel, so that the minimum frictional resistance will be offered to the flow of the high velocity stream, or may be allowed to rest upon the bed of the channel, either during the whole or during a portion 105 of the period of operation, so that a powerful erosive action will be developed against the channel bed, which will act to deepen the channel and to transport the material freed from the channel to the sea.

The economic value of a river valley is considerably reduced by the danger and constant fear of destructive floods. The river and the waters which are tributary thereto are laden with the most vital elements of the soil of the uplands, and the load thus transported is deposited in the lowlands as the river approaches its mouth. So long as these valuable lowlands remain exposed and unprotected they will be in danger of flood, and be swampy for a considerable period 110 of the year, so as to be inaccessible for continuous agricultural effort.

All previously proposed engineering systems for the regulation of river and stream flow have aimed to delay or intensify the forces of gravity acting upon the river waters. The system now proposed involves the addition of mechanical forces, so that the required hydraulic head can be estab- 115 120 125 130

lished and continuously maintained, whereby any required maximum of discharge can be obtained.

If the flow through the mouth of the river is thus accelerated by mechanical energy the river stream will not swell to such a point that the inflowing stream or storm or flood waters will exceed the capacity of the river channel, and they will find accommodation 10 within the river channel.

If the mouth of a river channel is not congested, and the flow through this mouth is accelerated in advance of the heavy inflow of flood waters, the line of least resistance for 15 these flood waters will be the lowest point in the path of their flow, and this will be the surface of the river stream, so that all of the inflowing storm waters that can be drained directly into the river channel will flow 20 within the channel banks and overflow will be effectively prevented.

The problem, therefore, of regulating the flood flow is one of acceleration to the point that the diameter of the river stream is contracted by reason of accelerated velocity, so 25 that this contracted stream, while giving the full or maximum flood discharge, has a cross sectional area not exceeding the cross sectional area of the river channel.

30 When the velocity of flow in the river channel is artificially accelerated by means of the system described the depth of the stream will be limited by the diameter of the contracted stream produced by this acceleration. As the velocity of any stream is increased, without an increase in volume of inflow, the diameter of the stream is lessened, and this contraction in the cross sectional area of a stream develops in depth more 35 positively than in width, so that the surface of the stream falls as the acceleration 40 causes it to contract.

When the surface of a river stream is thus maintained safely below that of its banks 45 and the adjoining lands, it is easier for the inflowing storm waters to flow through the river channel than to overflow the banks and inundate the adjoining territory. The contraction of the cross sectional area of the 50 river stream thus insures that the height of the stream surface will always be maintained within safe limits. In short, this surface height is wholly dependent upon the velocity of discharge through the river 55 mouth or outlet. It is the slowness of this outflow which, by impeding the flow through the channel, limits the capacity of the channel below that required by the inflowing flood or storm waters, and it is 60 wholly because of this lack of accommodation and capacity that inundation results. While local jetty systems and levee systems may locally intensify the velocity of flow, by increasing the hydraulic head of the river, 65 the incessant erosive action of the river is

bound to impair the utility of any such systems, and to soon render them useless.

When the height of the surface of the river stream is thus held within safe limits by this system of acceleration of flow, the 70 drainage of adjoining lands can be effected more positively. Moreover, the destructive action of the flood waters upon agricultural lands will be held within safe limits, as the side flow of the flood waters over the agricultural lands adjoining the river channel will be greatly limited, owing to the fact that the river channel will always have adequate capacity to accommodate the maximum of the flood waters.

80 The physical effect of this will be that the load removed from the valuable soils of the agricultural lands will be lessened, and the amount of sediments, gravel and other substances deposited in the bed of the river 85 channel will be greatly reduced.

By these results the economic status of the system will be greatly enhanced, the cost of dredging the river channel so as to maintain an adequate depth for navigation, will 90 be reduced, and the productivity of valuable agricultural lands maintained at their highest point.

When the depth of the mouth of a river 95 is such that the high velocity stream will interfere with surface navigation either in the river channel or in the sea into which the river empties, then the discharge pipes of the pumps can be lowered so that an adequate depth will be eroded and maintained, 100 and the high velocity stream will not interfere with surface navigation. The adjustment of such problems is wholly a matter of local engineering, gauging, and control.

Another and very important result obtained is that the system insures against a closing of the mouth of a river by river deposits, realized in the formation of a bar, or shallow depth, so that there is ready at all times means for clearing away a bar, by 110 simply operating the pumps. When it is not desired to operate the pumps the discharge and intake pipes may be elevated and inspected for any required repairs.

In Fig. 7 an electric motor drive is shown 115 wherein the motor C_m is connected by means of a belt to the centrifugal pump or accelerator C . The power plant employed in connection with each pump is operated through the medium of electrical energy generated at a 120 point distant from the section of the river channel in which the system of acceleration is applied, so that energy is added to the stream instead of taken from the stream: or such power plant is operated through the 125 medium of fuel consumed in the usual manner and the power thus generated is transmitted to the stream so as to accelerate its flow. The pumps and power plants may be arranged in dry pits or otherwise in the 130

stream channel, or upon islands existing in the stream channel.

Having described my invention I claim:

1. The method of preventing overflow on lowlands lying adjacent to a stream consisting in accelerating by means of an artificial hydraulic head generated directly in the stream, the velocity of the stream.
2. The method of preventing overflow on lowlands lying adjacent a stream consisting in controlling the height of the stream surface by accelerating the velocity of flow of the stream through its channel mouth by mechanical acceleration.
3. The method of preventing overflow on lowlands lying adjacent a stream consisting in placing in the stream to be regulated mechanical flow accelerators and operating said accelerators by means of power derived from a source independent of the energy of the stream at the point the accelerators act upon the stream.
4. The method of preventing overflow on lowlands lying adjacent a stream consisting in disposing a pump discharge conduit means in the stream channel facing in the direction of flow, disposing intake conduit means in the stream and causing the stream waters to flow through the discharge conduit means from the intake, conduit means at a velocity of flow greatly beyond that of the stream.
5. The method of preventing overflow on lowlands lying adjacent a stream consisting in disposing pump intake and discharge conduit means in the stream channel facing in the direction of flow of the stream, arranging continuously acting pumping devices between intake and discharge conduit means, and operating said devices to accelerate the velocity of flow of the stream at the points acted on beyond the velocity of flow produced by the forces of gravity acting on the stream to produce flow.
6. The method of preventing overflow on lowlands lying adjacent to a stream consisting in generating from the waters of the stream to be regulated a high velocity stream of less cross sectional area than the stream by means of mechanical accelerators operated so as to add to the energy of the stream so regulated.
7. The method of preventing overflow on lowlands lying adjacent to a stream consisting in generating from the waters of

the stream to be regulated a high velocity stream of less cross sectional area than the stream by means of mechanical accelerators and varying the relation of said high velocity stream to the bed of the stream channel to intensify or modify the erosive action of said high velocity stream upon the channel bed.

8. The method of preventing overflow on lowlands lying adjacent to a stream consisting in disposing pumping means in line with the stream to be regulated with the intake of said pumping means facing upstream and the outlet of said pumping means facing down stream and operating said pumping means to increase the total energy acting on the stream to produce flow, whereby the stream velocity will be increased beyond that possible from the pressure due to gravity alone.

9. The method of preventing overflow of lowlands lying adjacent a stream consisting in inducing high velocity current in the stream to be regulated, in the direction of the mouth of the stream by mechanical accelerating means immersed in the stream and acting directly thereon.

10. The method of influencing the carrying capacity of a natural stream channel in which water is flowing under pressure of gravity consisting in accelerating the natural flow of the stream waters by accelerating means immersed in the stream, and operating said means by energy from a source external to the stream itself at the point of location of said means.

11. The method of preventing overflow on lowlands of a flowing stream which consists in confining the flood waters of the stream within its banks by increasing the velocity of flow through the mouth of the stream channel by means of mechanical accelerators.

12. The method of influencing stream flow in stream channels in which water is flowing under the influence of gravity, consisting in energizing a current of water downstream to flow at a higher velocity than the velocity due to gravity alone and varying the relation of said current to the bed of the channel to vary the erosive action of the stream waters upon the channel bed.

JOSEPH J. O'BRIEN
